UNITED STATES PATENT OFFICE.

HARRY GIBSON, OF LOS ANGELES, CALIFORNIA.

GARMENT HANGER.

Application filed May 24, 1924. Serial No. 715,543.

My invention relates to an improvement in garment hangers, in which a plurality of garments may be quickly and efficiently suspended in a closet or other place found desirable.

It is an object of my invention to provide a device consisting of a plurality of parts, certain of which may be extended when the device is in use, and collapsed when it is out 10 of use, thereby making it possible to store the same in a small space.

A further object of my invention is to provide an improved device for suspending one or more pairs of trousers, a coat, and also 15 various feminine garments.

It is also an object of my invention to provide a garment hanger combined with a means for suspending the same, such means preferably taking the shape of a hook, which 20 hook, when the device is in use, may be swung above said device, and when out of use may be swung below and inside thereof.

It is also an object of my invention to provide the coat hanger part of my device with 25 one or more extension or side members, whereby the length of said coat hanger may be increased.

A still further object of my invention is 30 to provide a device in which a pair of end pieces is provided with a means whereby a woman's skirt may be suspended, and also with a set of spring clamps to suspend one or more pairs of trousers.

More specifically, it is an object of my invention to provide a garment hanger combined in which a top member is provided 35 with one or more side members in order that said top member may be lengthened, and two end pieces adapted to embrace a lower intermediate member, which member is adapted 40 to coact with one or more spring members, which in turn are adapted to hold in place a plurality of pairs of trousers. It is also within the province of my invention to provide 45 said end pieces with means whereby a woman's skirt may be supported.

It is also an object of my invention to provide a device which is simple in construction, efficient in operation, inexpensive to manufacture, and incapable of being easily gotten 50 out of order.

Further objects of my invention, and the advantages thereof will become apparent as the description thereof proceeds.

Reference is had to the accompanying drawings in which similar reference char-

acters denote similar parts. In the drawings:

Fig. 1 is a top view of my device with the side members shown in retarded position, 60

Fig. 2 is a side view of my invention, the various parts being shown collapsed and ready for storing,

Fig. 3 is a view similar to Fig. 2, but on a somewhat smaller scale, showing the device extended and ready for use, said view being taken on the opposite side of Fig. 2, 65

Fig. 4 is a bottom plan view of Fig. 2, the spring clamps being shown as sprung away from the end pieces, preparatory to clamping the plurality of pairs of trousers in place, 70 and

Fig. 5 is an end view of my device on an enlarged scale from that shown in the remaining figures. 75

Describing my device more in detail, a top member 1, made out of suitable material, such for example, either sheet material or wire, is provided with a pair of depending end pieces or members 13, which end pieces may be made integral with said top member 1 or secured thereto in any desired manner. 80

Between the end pieces 13, and embraced thereby, is positioned an intermediate member 8, which may be made integral with said end pieces or secured thereto in any desired manner, such, for example, as by the riveted portions 12. 85

A pair of spring members or clamps 7 and 7' are hinged to the end pieces 13 by loops 9 or any other suitable means. The other ends of said clamps are cut away to provide lock members 11, to engage with key hole slots 10, though it is clear that other means may be provided for locking said clamps in place. 90

As shown in Fig. 4, the clamps 7 and 7' are hinged at opposite ends, though it is clear that, if desired, they may be hinged on the same end pieces. Said clamps provide a means for clamping the trousers in place. The intermediate member 8 is shown of a somewhat greater width than the spring clamps 7 and 7', in order to secure the trousers more securely in place, though they may be made of the same width as said clamps if desired. 100

As will be understood, the top member 1 is to be used for hanging a man's coat or a woman's upper garment. To facilitate this purpose a pair of side members 2 and 2' is provided, which side members are provided with cut portions 5 and 5', which cut por- 105

tions may be crimped about the top member 1 loosely, to provide a means whereby the length of said top member may be increased. It is to be distinctly understood, however, that any other means may be provided whereby said side members may be made to slide on said top member for increasing the length thereof.

The top member 1 is preferably cut away as shown to provide slots for receiving an attaching member 4, which member is bent at right angles to form a hook 3, which functions as a means for supporting my garment hanger combined. It is obvious that, if desired, other means for suspending my device may be provided, and I do not propose to limit myself to the exact form shown and described.

When the device is in use, the hook 3 is swung into the position shown in Fig. 3, and when out of use it is swung into the position shown in Fig. 2.

To provide a means for suspending the skirt of a woman's dress, the end pieces 13 are provided with cut-away portions 6, which are adapted to receive the loops with which such a garment is ordinarily provided. It is clear, however, that I do not desire to limit myself to such cut-away portions, as in practice the well-known form of spring clamps or other means may be substituted therefor.

In use, the clamps 7 and 7' are swung out from the slots 10 and away from the intermediate member 8. It takes but a moment to place the trousers between the clamps and the intermediate member 8, or if such intermediate member is omitted, between such clamps, after which they are locked in position by means of the portions 11 and the slots 10.

By extending the side members 2 and 2', a coat of any sort may be suspended; and, if desired, a woman's skirt may be suspended by means of the cut-away portions 6, after which the hook 3 may be swung above the top member 1 and the garments suspended in any place found desirable.

It will thus be seen that I have provided a device which is simple in form, easy and inexpensive to construct, and of a very useful character.

It is obvious that my device may be modified throughout a wide range, and I therefore do not desire to be limited to the exact details of construction shown and described.

What I claim as my invention, and what I desire to be protected by Letters Patent is:

1. In a device of the class described, in combination, a top member, end pieces depending therefrom, a lower member positioned between said end pieces and em-

braced thereby, said end pieces being provided with cut-away portions functioning to support the loops of a garment, and a hook pivotally mounted upon said top member, the pivot of said hook being at right angles thereto, whereby said hook may be swung above said top member, when the device is in use, and below said top member and between said end pieces, when the device is out of use.

2. In a device of the class described, in combination, a top member, end pieces depending therefrom, said end pieces being provided with means for suspending a garment, a lower member extending between said end pieces and embraced thereby, and means for supporting said device, which means is adapted to be extended above said device or folded downwardly and positioned below said top member and between said end pieces.

3. In a device of the class described, in combination, a top member, flat end pieces depending therefrom, said end pieces being provided with cut-away portions for suspending a garment by means of its loops, and a hook pivotally mounted upon said top member, said hook, when the device is in use being adapted to be positioned above said top member, and when said device is out of use being adapted to be positioned below said top member.

4. In a garment hanger, in combination, a top member provided with a cut-away portion, means associated with said cut-away portion for supporting said hanger, end pieces associated with said top member, said end pieces being provided with means whereby one or more garments may be suspended therefrom, at least one side member associated with said top member and adapted to slide thereon, an intermediate member associated with said end pieces, and a pair of clamping members associated with said end pieces and adapted to co-act with said intermediate member to clamp a plurality of pairs of trousers therebetween.

5. In a garment hanger, in combination, a top member, means associated therewith whereby the length of said top member may be increased, end pieces depending from said top member, said end pieces being provided with one or more cut-away portions for suspending a garment, an intermediate member below said top member and positioned between said end pieces, and a pair of spring clamping members associated with said end pieces and adapted to coact with said intermediate member for clamping a plurality of pairs of trousers therebetween.

HARRY GIBSON.
